CLAIM

The ornamental design for a mortar and pestle, as shown and described.

DESCRIPTION

FIG. 1 is a front top perspective view of a mortar and pestle in a first configuration.

FIG. 2 is a rear bottom perspective view of the mortar and pestle as configured in FIG. 1.

FIG. 3 is a front view of the mortar and pestle as configured in FIG. 1. A rear view of the mortar and pestle as configured in FIG. 1 is the same as the front view.

FIG. 4 is a right side view of the mortar and pestle as configured in FIG. 1. A left side view of the mortar and pestle as configured in FIG. 1 is the same as the right side view.

FIG. 5 is a top view of the mortar and pestle as configured in FIG. 1.

FIG. 6 is a bottom view of the mortar and pestle as configured in FIG. 1.

FIG. 7 is a sectional view taken along line 7-7 of FIG. 3.

FIG. 8 is a sectional view taken along line 8-8 of FIG. 4.

FIG. 9 is a sectional view taken along line 9-9 of FIG. 3.

FIG. 10 is a front top perspective view of the mortar and pestle of FIG. 1 in a second configuration.

FIG. 11 is a front bottom perspective view of the mortar and pestle as configured in FIG. 10.

FIG. 12 is a front view of the mortar and pestle as configured in FIG. 10. A rear view of the mortar and pestle as configured in FIG. 10 is a mirror image of the front view.

FIG. 13 is a left side view of the mortar and pestle as configured in FIG. 10.

FIG. 14 is a right side view of the mortar and pestle as configured in FIG. 10.

FIG. 15 is a top view of the mortar and pestle as configured in FIG. 10.

(Continued)

FIG. 16 is a bottom view of the mortar and pestle as configured in FIG. 10.
 FIG. 17 is a sectional view taken along line 17-17 of FIG. 12.
 FIG. 18 is a sectional view taken along line 18-18 of FIG. 13.
 FIG. 19 is a sectional view taken along line 19-19 of FIG. 12.
 FIG. 20 is a front top perspective view of the pestle of the mortar and pestle of FIG. 1.
 FIG. 21 is a rear bottom perspective view of the pestle of FIG. 20.
 FIG. 22 is a front view of the pestle of FIG. 20. A rear view of the pestle of FIG. 20 is the same as the front view.
 FIG. 23 is a right side view of the pestle of FIG. 20. A left side view of the pestle of FIG. 20 is the same as the right side view.
 FIG. 24 is a top view of the pestle of FIG. 20.
 FIG. 25 is a bottom view of the pestle of FIG. 20.
 FIG. 26 is a front top perspective view of the mortar of the mortar and pestle of FIG. 1.
 FIG. 27 is a bottom rear perspective view of the mortar of FIG. 26.
 FIG. 28 is a front view of the mortar of FIG. 26. A rear view of the mortar of FIG. 26 is the same as the front view.
 FIG. 29 is a right side view of the mortar of FIG. 26. A left side view of the mortar of FIG. 26 is the same as the right side view.
 FIG. 30 is a top view of the mortar of FIG. 26.
 FIG. 31 is a bottom view of the mortar of FIG. 26.
 FIG. 32 is a sectional view taken along line 32-32 of FIG. 29.
 FIG. 33 is a sectional view taken along line 33-33 of FIG. 28.
 FIG. 34 is a perspective sectional view taken along line 34-34 of FIG. 28; and,
 FIG. 35 is a perspective sectional view taken along line 35-35 of FIG. 29.
 The broken lines and unshaded surfaces bounded by broken lines form no part of the claimed design.

1 Claim, 20 Drawing Sheets
